(57) **CLAIM**

The ornamental design for a lighting fixture, as shown and described.

DESCRIPTION

FIG. 1 is a perspective view from above of the lighting fixture; FIG. 2 is a perspective view from below of the lighting fixture of FIG. 1;

FIG. 3 is a right-side elevation of the lighting fixture of FIG. 1, the left-side elevation view being a mirror image thereof; FIG. 4 is a bottom plan view of the lighting fixture of FIG. 1; FIG. 5 is a top plan view of the lighting fixture of FIG. 1;

FIG. 6 is a perspective view from above of a second embodiment of the design of FIG. 1, the only difference being in proportional size of the finned portion;

FIG. 7 is a perspective view from below of the lighting fixture of FIG. 6;

FIG. 8 is a right-side elevation of the lighting fixture of FIG. 6, the left-side elevation view being a mirror image thereof; FIG. 9 is a bottom plan view of the lighting fixture of FIG. 6; FIG. 10 is a top plan view of the lighting fixture of FIG. 6; FIG. 11 is a front elevation of the lighting fixture of FIGS. 1 and 6; and,

FIG. 12 is a rear elevation of the lighting fixture of FIGS. 1 and 6.

The phantom lines are provided for illustrative purposes only and form no part of the claimed design.

1 Claim, 7 Drawing Sheets
